Des. 221,868

Patented Sept. 14, 1971

221,868

FIBER OPTIC CHRISTMAS TREE ORNAMENT

Shirlee E. Fairchild and Virginia M. Lawn, Huntington Beach, Calif., assignors to Poly-Optics, Inc.

Filed Apr. 30, 1970, Ser. No. 22,721

Term of patent 14 years

Int. Cl. D11—05

U.S. Cl. D29—1

Fig. 1.

Fig. 3.

Fig. 2.

FIG. 1 is a top perspective view of a fiber optic Christmas tree ornament showing my new design, the side opposite being substantially similar thereto;

FIG. 2 is a second embodiment of the design shown in FIG. 1; and

FIG. 3 is a top plan view of FIG. 1.

We claim:

The ornamental design for a fiber optic Christmas tree ornament, substantially as shown and described.
